DRAWER FOR A CABINET OR SIMILAR ARTICLE

Robert L. Propst, Ann Arbor, and James O. Kelley,
Saline, Mich., assignors to Herman Miller Inc., Zee-
land, Mich.

Filed Oct. 26, 1970, Ser. No. 25,646

Term of patent 14 years

Int. Cl. D6—04

U.S. Cl. D6—191

FIG. 1.

FIG. 7.

FIG. 2.

FIG. 3.

FIG. 4.

FIG. 5.

FIG. 6.

FIG. 1 is a perspective view of a drawer for a cabinet or similar article showing our design;

FIG. 2 is a front view of the drawer with the central portion broken away for convenience of illustration;

FIG. 3 is a side view of the drawer;

FIG. 4 is a rear view of the drawer with the central portion broken away for convenience of illustration;

FIG. 5 is a top plan view of the drawer;

FIG. 6 is a bottom plan view of the drawer; and

FIG. 7 is a perspective view of an alternative embodiment of the drawer.

We claim:

The ornamental design for a drawer for a cabinet or similar article, substantially as shown.
